UNITED STATES PATENT OFFICE

93,361

DESIGN FOR AN OFFICE SWIVEL CHAIR

Benjamin R. Smith, Owensboro, Ky.

Application July 16, 1934, Serial No. 52,604

Term of patent 7 years

To all whom it may concern:

Be it known that I, BENJAMIN R. SMITH, a citizen of the United States, residing at Owensboro, in the county of Daviess and State of Kentucky, have invented a new, original, and ornamental Design for Office Swivel-Chairs, of which the following is a specification, reference being had to the accompanying drawing, forming part thereof, in which drawing—

Fig. 1 is a perspective view of an office swivel-chair showing my new design;

Fig. 2 is a side elevation thereof; and

Fig. 3 is a partial plan view showing one-half of the chair shown in Fig. 1.

I claim:

The ornamental design for an office swivel-chair, as shown.

BENJAMIN R. SMITH.
